UNITED STATES PATENT OFFICE

CHARLES W. ELDER, OF ROY, WASHINGTON, ASSIGNOR OF ONE-HALF TO J. RAY BENNETT, OF ROY, WASHINGTON

WRAPPING-PAPER-FEED DEVICE

Application filed February 25, 1926. Serial No. 90,526.

This invention relates to store service and especially to devices and apparatus for holding and feeding wrapping paper to the store clerk, when needed, and has for its objects to provide such an apparatus which will permit the wrapping paper to be stored beneath the service counter, thus leaving the counter free for the display of goods to the purchaser; in which a plurality of widths or kinds of wrapping paper may be used and any of them fed to the clerk; which, when operated, will cause a short length of the desired wrapping paper to extend up through a slot in the counter, which is spring mounted and will therefore give way when the paper is pulled upward, and will thus prevent the wrapping paper from becoming wrinkled; in which the feed rollers may be manually separated to permit the end of a new roll of paper to pass through the device and into position therein; in which the pressure of the feed rollers may be controlled to suit the weight of the particular kind of paper; in which more than one sheet may be fed simultaneously up through the slot in the counter so that double wrapping of food or oily substances, as with paraffine paper and brown wrapping paper, may be done at one time thus saving both time and labor; in which the edges of the slot in the counter are sharp and thus facilitate the tearing off of the paper at the desired point with the least effort; in which the resistance in the apparatus is sufficient to cause the paper to be torn or cut off at right angles to the sheet without unrolling the paper as it is being torn; in which a plurality of sheets are fed through a single slot in the store counter. A further object is to provide an apparatus which is cheap to make, easy to install and to operate, effective in use, and rugged in construction.

I attain these and other objects by the devices, mechanisms and arrangements illustrated in the accompanying drawings, in which—

Fig. 1 is an elevation of the rear side of a store counter, showing my apparatus in position therein with three different rolls of paper fed therethrough, and showing the paper from one of the rolls fed up through the

counter and ready to be pulled out therefrom to provide the desired wrapping paper; Fig. 2 is a section of the apparatus, showing the various sets of feed rollers; Fig. 3 is a bottom view of one pair of said feed rollers; and Fig. 4 is an elevation of one end of the apparatus showing the roller operating mechanism for one pair of said feed rollers. Similar numerals of reference refer to similar parts throughout the several views.

It will be seen that the store counter 1 is entirely free of the usual standards containing rolls of wrapping paper of different widths, on its upper or display surface, and that it is provided with the usual service shelves 2 below it, said shelves being shown as open to the rear. A portion 3 of the space below the counter 1 is free from the said shelves 2, and in this space 3 I mount the rolls of wrapping paper, 4, 5 and 6, to be used by the sales clerk, on any convenient stands or holders. A narrow slot 7, of inverted V-shape section, is provided through the counter 1, said slot being lined with strips of metal 8, each of which has a sharp cutting edge 9, on a level with the top of the counter 1, said cutting edges 9 forming the sides of the opening or slot 7, through which the wrapping paper is to be pulled. The cutter, thus formed, is adapted to facilitate the tearing of the paper at the level of the counter when the paper is appropriately brought into cutting contact therewith.

A frame, comprising a pair of plates 10, hangs down from the lower side of the counter 1, at each end of the slot 7, and carries, between the said plates 10, several pairs of feed rollers, as hereinafter described, as well as suitable transverse plates 11 arranged and shaped to form guides for the paper fed by the several pairs of rollers and directing each sheet to the single slot 7. The drawings show a mechanism adapted to use three separate rolls of paper and there are therefore two such guide plates 11, each leading the sheet to the slot 7 in the counter.

A separate set of feed mechanism, whereby a short length of any one or more of the sheets may be unrolled and fed through the slot 7, to extend above the counter 1, is pro-

vided for each of the rolls 4, 5 and 6 of paper but since they are similar in all particulars, except position, a description of one set alone will be understood to apply to each of the others.

The feed rollers are arranged in pairs and the pairs are grouped near the slot 7 and positioned to direct the paper fed thereby towards the said slot 7. One roller 12, of the 10 pair, is fixedly mounted between the frame plates 10 and is free to rotate therein under the action of the hereinafter described actuating means, but the other feed roller 13 is mounted in slide blocks 14. Each block 14 is 15 mounted in a slot 15 in the frame plate 10 and is pressed towards the feed roller 12 by means of a spring 16, whose force is controlled by a screw 17. The two feed rollers 12 and 13 are each provided with deep meshing 20 gears 18, at one end, whereby they are caused to turn together when the roller 12 is actuated, and whereby they together resist turning when not operated by the actuating means, as when the paper is being manually 25 pulled out of the slot for use. The axis of the slot 15 is approximately at right angles to the center of the arc-of-contact of the sheet of paper 19 with the said spring mounted feed roller 13. Thus, when the sheet 19 is manually 30 pulled upward through the slot, after its end has been fed therethrough by the feed rollers, against the resistance of the roll of paper 4, 5 or 6, as the case may be, the tension in the paper 19 will force the feed roller 35 13 away from the feed roller 12, against the action of the springs 16.

A rod 20 is journaled in the two blocks 14, adjacent to the roller 13, and is provided at its inner end with an arm 21 and at its outer 40 end with a hand lever 22, parallel with but longer than the said arm 21. Two pins 23 are fastened, in corresponding positions, on the two frame plates 10 and are positioned to be engaged respectively by the said arm 21 45 and hand lever 22. Thus when the lever 22 is moved in the direction of the arrow in Fig. 4, it rotates the rod 20 in its bearings in the blocks 14 until it and the arm 21 come in contact with the pins 23, as shown, and then further motion causes the pins 23 to act as fulcrums and the rod 20, with the blocks 14 and the roller 13, are retracted against the actions of the springs 16, thus opening up the 50 space between the rollers 12 and 13 and permitting the end of a new sheet to be inserted therebetween.

Each of the rolls 4, 5 and 6 is provided with a spring pressed rod, indicated at 24, engaging the paper 19 thereof as it unrolls therefrom, and acting as a resistance to the pull on the paper so that, when the desired length of paper has been unrolled and pulled out of the slot, the clerk may strain the edge of the 55 sheet 19 against the cutting edge 9 and cause

the sheet to tear along the said sharp edge without unwinding any more from the roll.

The feed rollers 12 and 13 turn stiffly in the frame plates 10 and are actuated by a ratchet mechanism comprising a ratchet wheel 25 secured on the roller 12 and a ratchet lever 26 loosely journaled thereon. This lever 26 has a ratchet dog 27 mounted on it and adapted to engage and operate the wheel 25 and the roller 12, in one direction, whenever the lever 26 is actuated. 70 75

A bar 28 is mounted in horizontal position slightly below the counter 1, at any convenient point. As shown in the drawings the bar 28 is located to the right of the feed apparatus. The right-hand or far support 29 of the said bar 28 may be slid into any desired position before being attached to the lower side of the counter 1. An operating rod 30 is connected to the end of the above described ratchet lever 26 and extends towards the right and then turns up at right angles to form a handle 31 which is loosely supported on the said bar 28 in such manner as to be free to slide thereon (Fig. 4). A spring 32 is connected at its two ends to the handle 31 and the support 29, always drawing the rod 30 towards the right. The tension of the spring 32 will depend on the position of the support 29 on the bar 28. A buffer or cushion spring 33 may be mounted on the bar 28 on the left side of the handle 31. 80 85 90

Thus it will be seen that by pressing the vertical handle 31 of the rod 30 towards the left, against the action of the spring 32, the ratchet lever 26 is caused to actuate the feed rollers 12 and 13, through the gears 18, to draw the sheet 19 up from the roll of paper and extend it a short distance above the counter 1, as shown in Fig. 1. Also, that as soon as the rod 30 is released, the spring 32 draws it to the right and swings the ratchet lever 26 into position to take a new hold on the said ratchet mechanism. When a short length of the paper 19 is thus exposed above the counter 1, it may be grasped by the clerk and pulled upward, thus unwinding the roll 4, 5 or 6 from which it comes. However, if the roller 13 were not spring mounted, as above described, the effect of pulling on the sheet 19 would be to cause the rollers 12 and 13 to rotate, and thus cause the paper to become wrinkled or creased, but being spring mounted, the roller 13 moves away from the roller 12 and permits the paper to slide thereon, under which conditions the paper 19 does not wrinkle or crease, especially if the rollers 12 and 13 do not rotate. 100 105 110 115 120

In practice I prefer to make the rollers 12 and 13 of wood and to cover them with a felt or other cloth casing, suitably cemented or otherwise secured thereon. 125

Having therefore described my invention, what I claim is:

1. In a wrapping paper feed device, the 130

combination with a frame having two parallel complementary parts; a fixed feed roller rotatably mounted in said frame between the parts; sliding blocks mounted in said frame and movable in a direction substantially radial to said fixed feed roller; springs actuating said blocks; a second feed roller rotatably mounted in said blocks and pressed towards the first feed roller by said springs; a rod 5 mounted in said blocks adjacent said second feed roller; parallel arms extending from the ends of said rod; and complementary pins in said two frame parts, whereby when one arm is actuated to press against its complementary pin, the other arm is similarly moved, and the pins become fulcrums whereby the blocks are moved against the action of said springs and the two feed rollers are separated thereby permitting the insertion 10 of the end of a strip of paper therebetween.

2. In a paper dispensing device the combination of a pair of feed rolls normally in frictional engagement with each other, one of said feed rolls having yieldable mountings, a paper delivery table through which paper may be fed by said feed rolls, guides for directing the fed paper through said table, a cutting edge where said paper emerges from said table, said cutting edge lying in a 15 plane passing between said feed rolls normal to a plane including their axes, a support for a paper supply roll, the cutting edge, feed rolls and support being so constructed and arranged that by pulling the web of paper 20 past said cutting edge the feed rolls will be separated and permit a relatively free passage of the web between said rolls.

CHARLES W. ELDER.
